[57] CLAIM

The ornamental design for a high heeled calf length sneaker, as shown and described.

DESCRIPTION

FIG. 1 is a left side elevational view of a high heeled calf length sneaker showing my new design, the right side being substantially a mirror image thereto;

FIG. 2 is a front elevational view thereof;

FIG. 3 is a top plan view thereof;

FIG. 4 is a rear elevational view thereof;

FIG. 5 is a bottom plan view.

FIG. 2

FIG. 1

FIG. 4

FIG. 3

FIG. 5
